UNITED STATES PATENT OFFICE.

TYRE C. HUGHES, OF TULSA, OKLAHOMA, ASSIGNOR OF ONE-HALF TO JOHN B. JAMESON,
OF CONCORD, NEW HAMPSHIRE.

PISTON-RING.

1,280,739.

Specification of Letters Patent.

Patented Oct. 8, 1918.

Application filed June 3, 1915. Serial No. 31,854.

To all whom it may concern:

Be it known that I, TYRE C. HUGHES, a citizen of the United States, residing at Tulsa, in the county of Tulsa and State of Oklahoma, have invented a certain new and useful Improvement in Piston-Rings, of which the following is a specification.

My invention relates to improvements in piston rings. It relates particularly to transversely divided piston rings.

The object of my invention is to provide a novel construction of piston ring of the transversely divided type, which will not permit leakage past it as it opens when the ring or cylinder becomes worn.

My invention is adapted for various uses, and is particularly adapted for use in steam engines and automobile engines of the explosive type.

The novel features of my invention are hereinafter fully described and claimed.

In the accompanying drawing, which illustrates the preferred embodiment of my invention,

Figure 1 is a view looking at one edge of the ring, the ring being in its open position.

Fig. 2 is a view looking at the divided side of the ring.

Fig. 3 is an edge view of the ring in the closed position and applied to a piston which is shown in dotted lines.

Fig. 4 is an enlarged perspective of the end portions of the ring, shown in the open position.

Fig. 5 is an enlarged cross section on the line 5—5 of Fig. 3.

Fig. 6 is an enlarged cross section on the line 6—6 of Fig. 3.

Similar reference characters designate similar parts in the different views.

The transversely divided ring 1 is provided at one end and in the edge 2 and outer periphery with a notch 3, preferably having a transversely beveled surface which extends from near the outer periphery of the ring obliquely to the edge 2.

The other end of the ring is provided with a projection 4 which is, preferably, provided with a transversely beveled surface 5 fitted to the beveled surface of the notch 3, the projection 4 being fitted to the notch 3 so as to fill the same when the ring is mounted on the piston 6, shown in dotted lines in Fig. 3. The edge and outer surface of the

projection 4 form extensions of the edge 2 and outer periphery of the ring.

The end of the ring having the projection 4 is provided in the edge 7 and inner periphery of the ring 1 with a notch 8, disposed in stepped relationship to the projection 4, and which has fitted to it a projection 9 at the end of the ring having the notch 3. The notch 8 is preferably provided with a transversely beveled surface fitted to a similarly beveled surface 10 on the outer side of the projection 9. The beveled surface of the notch 8 extends from near the middle of the inner periphery obliquely to the edge 7 of the ring. The notch 8 does not extend to the outer periphery of the ring, and the notch 3 does not extend to the inner periphery of the ring. The projection 9 completely fills the notch 8 when the ring is fully closed, as shown in Fig. 3, and its outer edge and inner surface form extensions of the edge 7 and inner periphery respectively of the ring.

By reason of the construction described, when the ring is mounted in the groove 11, shown in dotted lines in Fig. 3, and fitted in a cylinder, not shown, the projections 4 and 9 will respectively overlap and fit the recessed portions 3 and 8.

As the ring or piston wears, the ring will open, but there will be no leakage as long as the ends of the ring overlap each other, there being no open passage by which fluid may pass from one side of the ring to the other side. Upon wear of the ring, or of the cylinder, the ring will expand slightly, and will not be a perfect circle. This would cause the joint of the ring to scratch or score the cylinder but for the fact that, upon the expansion of the ring, a small hole extends from the inner to the outer side of the ring at the middle of its joint, due to the employment of the two beveled notches. Oil is scraped from the cylinder wall and passes into this hole, from which it is again thrown against the cylinder wall, thereby keeping the joint well oiled, so that scoring or scratching of the cylinder is prevented.

I do not limit my invention to the structure shown and described, as modifications, within the scope of the appended claim, may be made without departing from the spirit of my invention.

What I claim is:—
A transversely divided piston ring having

two notches, one in one edge and inner periphery only, and the other in the other edge and outer periphery only, each of said notches having a transversely beveled surface, and two projections, one at each end of the ring, respectively fitted to said notches, one projection forming an extension

of the outer periphery and one edge of the ring, and the other projection forming an extension of the other edge and inner periphery of the ring.

In testimony whereof I have signed my name to this specification.

TYRE C. HUGHES.
